UNITED STATES PATENT OFFICE.

FRANZ A. BOEDTCHER, OF BERGENFIELD, NEW JERSEY.

ELEVATOR-INDICATOR.

1,089,310.

Specification of Letters Patent.

Patented Mar. 3, 1914.

Application filed January 6, 1913. Serial No. 740,476.

To all whom it may concern:

Be it known that I, FRANZ A. BOEDTCHER, a citizen of the United States, and a resident of Bergenfield, in the county of Bergen 5 and State of New Jersey, have invented a new and Improved Elevator-Indicator, of which the following is a full, clear, and exact description.

This invention relates to improvements in 10 elevator indicators, and has for an object to provide an improved structure adapted to automatically operate for indicating not only the floor at which the elevator may be positioned and the progress of the elevator 15 from one floor to the other, but to indicate the direction of travel of the elevator regardless of whether or not the same is moving or stationary, so that a person looking at the indicator may observe whether the particular elevator is making an up trip or a 20 down trip.

A further object of the invention is to provide an improved structure having a pair of signs displaying the words "Up" and 25 "Down", or similar information, and various mechanism in connection therewith operated by the usual indicating hand of an indicator, whereby the signs are brought to a predetermined position as the car to which 30 the device is attached moves up and down.

In carrying out the objects of the invention, an indicating mechanism is provided which includes a face and a rotating hand or pointer designed to move over the face 35 for indicating the floor at which the elevator may be positioned. An operating shaft is connected with the hand or indicating member for properly moving the same, and which in turn is connected with an 40 elevator in any usual or preferred manner. Associated with the hand or indicator and the operating shaft therefor, is a sign designed to rock so that the opposite ends or opposite sides may be brought to a particular point so as to disclose legends placed 45 thereon, namely, the words "Up" and "Down", or any other desired information. In one form of the invention a pin extends from the hand or indicating pointer so as to 50 strike or engage the tiltably mounted sign for shifting the position thereof, while in another form of the invention a tilttable sign is provided with pins designed to project into the path of movement of the pointer so 55 that when the pointer is moved to a certain position the tilttable sign is operated. In

either of the forms of the invention the same idea is present, namely, a sign with the words "Up" and "Down" arranged thereon, or similar words, and mechanism 60 for causing the up sign to be brought into view when the elevator starts upwardly, and to be maintained in that position until the next movement of the elevator should be a downward movement, whereupon the down 65 sign is brought to view and maintained in that position. By this construction and arrangement, not only the floor at which the elevator is positioned may be seen upon the indicator face, but also the direction in 70 which the elevator is traveling or is about to travel, in case the elevator is standing still.

A practical embodiment of the invention is represented in the accompanying drawings forming a part of this specification, in 75 which similar characters of reference indicate corresponding parts in all the views.

Figure 1 is a front view of an indicator embodying the invention; Fig. 2 is a plan view of the operating mechanism, the indicating hand or finger, and face plate being removed; Fig. 3 is a rear view of the structure shown in Fig. 1, part of the face plate being broken away; Fig. 4 is a section through Fig. 1 on the line 4—4; Fig. 5 is 80 a section through Fig. 1 on the line 5—5; Fig. 6 is a front elevation of an indicator embodying a slightly modified form of the invention to that shown in Fig. 1; Fig. 7 is a section through Fig. 6 on the line 7—7; Fig. 90 8 is an enlarged fragmentary sectional view showing means for yieldingly holding the signal plate in a predetermined position; and Fig. 9 is a sectional view similar to Fig. 7, except that the same shows a slightly 95 modified form of the invention to that disclosed in Fig. 7.

Referring to the accompanying drawings by numerals, 1 indicates the face of an indicator of any desired kind. The mechanism 100 2 of the indicator may be of any desired kind, that shown being similar to my Patent No. 1,037,113. This mechanism is intended to cause a central shaft 3 to rotate as the elevator moves up and down in the usual manner. As the elevator moves up and down, the indicating hand or finger 4 moves over the dial 5 of the face plate 1 for indicating the progress of the elevator. If the elevator was standing still in any particular 105 instance it would be impossible to ascertain whether or not the same was going up or

down by merely looking at the hand or indicating finger, so additional mechanism is provided for presenting a signal to indicate the direction of travel of the elevator. 5 This indicating mechanism is shown more clearly in Fig. 2, wherein 6 indicates an oscillating or tiltable sign having a legend 7 arranged at one end, and a legend 8 arranged at the other end, these legends being 10 of any desired kind, as for instance, the words "Up" and "Down." In Fig. 1, the sign 6 has been tilted so that the elevator is shown as on its upward travel and as being stationed at floor 2. When the elevator 15 reaches its extreme upward movement, namely floor 8, the sign will be operated so as to move the legend 8 (the sign "Up") to a position out of sight, and move legend "Down" to a position where the same may 20 be seen, namely to a similar position on the opposite side of the shaft 3 to the legend "Up." The sign 6 is mounted on shaft 24 so as to move therewith when such movement is not opposed, but to slip over when 25 such movement is opposed, the connecting means being arranged in a suitable casing or housing 9, as shown in Fig. 2. In Fig. 8 a detail structure of this means is shown which is adapted to operate the sign 6 shown 30 in Fig. 6, or to operate sign 10 shown in the modified structure disclosed in Figs. 5 to 9 inclusive. From Fig. 8 it will be seen that shaft 3 is surrounded by a casing 9, which casing is frictionally pressed against 35 the shaft 3 by a block 11. The block 11 is held in place by a spring 12 maintained under tension by a screw 13. By this means any desired pressure may be brought to bear on block 11 so as to cause the casing 9 to 40 more or less tightly engage or clamp the shaft 3. The casing 9 is provided with an extension 14 which is designed to engage a suitable notch 15 in the sign 10, shown in Fig. 6 and engage a suitable notch 16 in 45 the sign 6, shown in Fig. 2. A depending weight 17 assists in causing a proper movement of the sign 6. In addition to these means for operating the sign 6, a pin 18 is connected with the hand or finger 4, and extends a sufficient distance from the hand or finger 4 to 50 strike against the ends of the sign 6 so as to positively move the sign from one position to the other. In Fig. 1, for instance, when the hand or finger 4 begins to move past 55 floor 7, the same will begin to force the end of sign 6 containing the legend "Up" in a downward direction until the car stops at floor 8, whereupon the sign "Up" will be entirely out of sight, and the sign "Down" 60 will be brought to view on the opposite side of shaft 3. This will of course indicate to any one on any of the floors that the next movement of the car will be the beginning of the downward travel. When the car 65 reaches the bottom of its downward travel

the pin 18 will strike the end of sign 6 containing the legend "Down" and force that end downwardly out of view and consequently will cause the legend "Up" to appear on the opposite side of the shaft 3. 70 However, if the elevator should move upwardly to the second floor, as shown in Fig. 1, then start to move down, the pin 18 could not operate upon the end of the sign 6 containing the legend "Up," but the housing 9 and extension 14 and associated parts 75 would be moved by shaft 3 so as to move the legend "Down" to its elevated position and move the legend "Up" to the position out of sight so as to indicate that the elevator 80 was traveling in a downward direction.

In Figs. 5 to 7, will be seen a slightly modified form of the invention in which the face 19 is closed with the exception of slots 20 and 21, and opening 22. Pivotal 85ly mounted on the rear of face 19 is a sign 10 journaled on a suitable bolt or journal member 23 in a similar manner to the way sign 6 is journaled on member 24 in Fig. 2, the member 4 being supported by any desired 90 kind of bracket or other support. The upper end of sign 10 is provided with the legends "Up" and "Down" which are adapted to be brought opposite the apertures 22 so as to indicate the direction of 95 travel of the elevator when moving or standing still. The lower part of the sign 10 is provided with a notch 15 in which the extension 14 fits, as shown in Fig. 8, so as to cause the proper operation of the sign in 100 case the elevator should be reversed intermediate its travel, namely at any of the floors except the first and last. Pins 25 and 26 are rigidly secured to the lower part of the sign 10 and extend through slots 20 105 and 21 respectively, so as to be in the path of movement of the indicator or finger 27. The indicator or indicating finger 27 is designed to operate in a similar manner to finger 4 and to engage and move pins 25 and 110 26 and the sign connected therewith to form the completion of the travel of the elevator. If the pins 25 and 26 were not used the elevator could reach the top floor and remain stationary and the signs remain unchanged. 115 By the use of the pins 25 and 26 the sign will be automatically changed as the elevator reaches the top floor.

Where it is desired to use the sign 10 as shown in Fig. 6, and it is not desirable to 120 have slots 20 and 21 arranged in the face plate 15, a second indicator or finger 28 (Fig. 9) is rigidly secured to shaft 3, this indicating finger being arranged directly in back of the indicating finger 27 and intended to engage pins 25 and 26 which are sufficiently shortened as not to engage the face plate 19. This will have exactly the same effect as the structure shown in Fig. 6, without the use of the slots 20 and 21. 125 130

Having thus described my invention I claim as new and desire to secure by Letters Patent:—

1. In an indicator of the class described, 5 the combination with a rock shaft, of a pivotally mounted sign member having a legend arranged on each end, a screen normally concealing both legends, means connected with said shaft and engaging said sign member for rocking the sign member and thereby causing one of said legends to be brought to view upon each reversal of said shaft, and a weight connected to said sign member for giving the same a tendency to remain in a 15 neutral position.

2. In an indicator of the class described, the combination with an indicating hand, a rotating shaft for operating said hand, of a sign member formed with a legend on each 20 end, means frictionally engaging said shaft and operatively engaging said sign member for causing said sign member to be tilted from one position to the other upon each reversal of movement of said shaft for indicating the direction of travel of the elevator 25 to which the indicator is connected.

3. In an indicator of the class described, the combination with a rotating shaft and an indicating finger, of a tilttable sign 30 formed with legends on opposite portions thereof, a pin connected with said sign adapted to be engaged by said finger for causing the finger to move said sign so as to move the legends from one position to another, and an auxiliary means frictionally connected with said shaft and engaging said sign for shifting the position of said sign whenever said shaft reverses its movement.

4. In an indicator of the class described, 40 the combination with a rocking shaft and an indicating finger of a tilttable sign formed with legends on opposite portions thereof, pins projecting from said sign, an auxiliary hand connected with said rocking shaft 45 adapted to engage the pin on said sign and move said sign upon the extreme movement of said shaft in either direction, and auxiliary means frictionally connected with said shaft and engaging said sign for shifting the position of said sign whenever said shaft 50 reverses its movement.

5. In an indicator of the class described, the combination with a rotating shaft and an indicating finger, of a tilttable sign

formed with legends on opposite portions 55 thereof, means for causing said indicating finger to move said sign so as to change the legend, and auxiliary means connected with said shaft and engaging said sign for shifting the position of said sign whenever said 60 shaft reverses its movement.

6. In an indicator of the class described, the combination with a rotating shaft, of a tilttable sign provided with legends on opposite parts thereof, and means engaging said 65 tilttable sign for causing the respective legends thereon to be brought to view upon each reversing of movement of said shaft, said means comprising a housing frictionally engaging said shaft, a yielding friction 70 member for clamping said housing to said shaft, and an extension engaging said sign.

7. In an indicator of the class described, the combination with a rotatable shaft, of a tilttable sign provided with legends on opposite 75 parts thereof, and means engaging said shaft and said sign for operating said sign, said means comprising a housing, an extension for engaging and shifting the position of said sign, a friction block arranged in 80 said housing and engaging said shaft, a spring pressing against said friction block, and means for regulating the tension of said spring whereby upon each reversal of movement of said shaft said extension will be 85 moved for shifting the position of said sign while the continued movement of said shaft in the same direction will cause said sign to remain in the position in which it has been placed. 90

8. In an indicator of the class described, the combination with a rotatable shaft and an indicating finger, of a pin operated by said rotatable shaft, a tilttable sign moved by said pin, said sign being positioned so as 95 to be operated by said pin upon the extreme movement of said finger, and means engaging said shaft and said sign for changing the position of said sign upon the reversal of movement of said shaft while said finger 100 is intermediate its extreme positions.

In testimony whereof I have signed my name to this specification in the presence of two subscribing witnesses.

FRANZ A. BOEDTCHER.
